CLAIM

The ornamental design for a case for electronic communications device, as shown and described.

DESCRIPTION

FIG. 1 is a front perspective view of the case for electronic communications device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged detail view of the encircled region of FIG. 2.

The dot-dash broken line circle in FIGS. 2 and 9 delineates a portion of the case for electronic communications device, including claimed subject matter, that is shown on an enlarged scale in FIG. 9.

With the exception of the interior button region and the interior edges of the various openings which are shown in solid lines, the interior surfaces of the case shown in FIGS. 1 and 3 and the dashed broken line shown in FIG. 1 form no part of the claimed design.
